APPARATUS FOR STARTING AND OPERATING
GASEOUS DISCHARGE DEVICESFred W. Abrahams, Chicago, Ill., assignor to Advance
Transformer Co., Chicago, Ill., a corporation of Illinois

Application December 28, 1954, Serial No. 477,989

13 Claims. (Cl. 315—97)

This invention relates generally to apparatus for starting and operating gaseous discharge devices, and particularly is concerned with such a device known as a ballast, which has unusual power factor correcting ability.

Generally the invention contemplates a ballast which is intended to serve two gaseous discharge devices—fluorescent lamps in the particular application for the apparatus built in accordance with the invention—connected in series.

Objects of the invention are: the provision of a ballast in which the amount of iron and necessary copper are held to a minimum; the provision of a ballast in which power factor correction is achieved in a novel manner due to the unusual arrangement of the windings on the core; the provision of a device in which power factor correction is achieved through the use of a smaller condenser than would ordinarily be used; and the provision of a device of the character described which is intended for use with gaseous discharge devices of the rapid start type, that is, for example, fluorescent lamps in which the filaments have current flowing therein continuously.

Further important objects are: the provision of a series connected pair of gaseous discharge devices in which there is a capacitance connected across one of the devices to aid in starting and in which there is capacitive means connected across the primary winding; the provision of a power factor correcting circuit for series connected discharge devices in which there is a current limiting impedance in series with the discharge devices, but in which there is no capacitance in the operating current circuit for the lamps; the provision of a circuit for igniting and operating gaseous discharge devices in which the primary is divided into two parts each of which is coupled in different degree to the secondary winding supplying the principal voltage for the discharge devices; the provision of a gaseous discharge device apparatus in which the windings are arranged relative to a shell core in a novel manner to achieve certain beneficial results.

Other objects will appear as the description of the invention proceeds, in connection with which there has been illustrated in considerable detail a preferred embodiment of the invention demonstrating the manner in which the same is carried into practical use and application.

In the drawing, in which none of the conventional core and shunt lines are shown in order to keep the illustration uncluttered:

Fig. 1 is an electrical circuit diagram of the apparatus of the invention.

Fig. 2 is a side elevational view of the transformer portion of the apparatus illustrated in Fig. 1.

The invention resides principally in the power factor correcting circuit and in the arrangement of the windings upon the transformer core, and hence it would perhaps be best to describe first the transformer and its windings.

As seen in Fig. 1 there are three filament windings F_1 , F_2 and F_3 ; there are two primary windings P_1 and P_2 ; and there are three secondary windings S_1 , S_2 and S_3 . The windings P_1 and S_1 are closely coupled together, being

wound on top of one another in a window of the transformer core as will be seen; the windings P_2 , S_2 and F_1 are also closely coupled together and wound one on top of another in the second window of the transformer core; and the windings S_3 , F_2 and F_3 are also closely coupled together and wound one on top of the other in a window of the transformer core. The relationships between the various groups of windings will shortly be brought out.

The transformer 10 comprises a stack of identical laminations of electrical sheet steel forming an outer shell 12 of rectangular formation and an inner winding leg 14 which extends the length of the shell 10 on the interior thereof. The laminations are held together by riveting or the like as indicated at 16, and the central winding leg 14 laminations are stamped out of the same blanks. The said central winding leg 14, after assembled with the windings, is pressed back into the rectangular shell 12, with its curved ends matingly engaging at 18 and 20 with the bridging ends 22 and 24 respectively of the shell 12. Proper seating is obtained in any suitable manner such as for example, by juxtaposed indexing notches 26.

There are several punched out portions along the core 10 between the winding leg 14 and the elongate sides 28 and 30 spaced apart by inward extensions 32 and 34 relatively narrow, and 36 and 38 relatively wide. The designated extensions are all integral with the shell 12, the former pair extending about halfway to the winding leg and there facing similarly aligned extensions 40 and 42 integral with the winding leg. The extensions 32, 34, 40 and 42 together form a magnetic shunt which will generally be designated 43, provided with non-magnetic spaced gaps 44 of high reluctance. The extensions 36 and 38 face notches 46 and 48 cut in the winding leg 14 being spaced therefrom by gaps 50 and thereby forming the magnetic shunt 52 with non-magnetic high reluctance gaps. The particular structure aids in placement of the windings on the various parts of the winding leg 14 prior to pressing same home into the core 12.

Between the shunt 43 and the bridging end 22 there are formed windows 54; between the shunts 43 and 52 there are formed windows 55; and between the shunt 52 and the bridging end 24 there are formed windows 56. The windings P_1 and S_1 are both in the windows 54; the windings P_2 , S_2 and F_2 are all in windows 55; and the windings S_2 , F_2 and F_3 are all in windows 56. Conveniently, the winding F_1 may be a continuation of the winding P_2 and the winding F_3 a continuation of winding S_3 . Connections are obtained by suitable taps.

The windings P_1 and P_2 actually form together a primary winding which has been split into two parts separated by the shunt 43 since both are in series and connected to terminals 60 and 61. The series connection between primary parts P_1 and P_2 is provided by jumper 64, the right hand terminal of the primary winding P_1 , P_2 is designated 65 and the left hand terminal 66. The two gaseous discharge devices L_1 and L_2 are of the continuous current filament type, the illustration intended to designate rapid start fluorescent lamps. Each lamp has a filament at opposite ends which must be continuously energized. L_1 has filament 67 connected by leads 68 and 69 across winding F_1 which provides a voltage induced by primary winding part P_2 ; and a second filament 70 connected in parallel with the filament 71 of the discharge device L_2 . Jumper 73 and 74 are connected by respective leads 75 and 76 with filament winding F_2 which is in transformer relation with winding S_3 . The filament 78 is connected across filament winding F_3 by leads 79 and 80.

The secondary winding S_1 is connected by lead 82 to terminal 66 and connects with junction point 84. Between junction point 84 and terminal 65 there is connected a power factor winding S_2 in series with a power factor condenser C_1 . This winding is of particular interest be-

cause of its unusual function which presently will be brought out.

The third secondary winding S_3 is connected by way of lead 86 between junction point 84 and terminal 88 which it has in common with filament winding F_3 .

The basic operating circuit is a series circuit including the two discharge devices L_1 and L_2 and the two secondary windings S_1 and S_3 in auto-transformer relationship with the primary windings P_1 and P_2 . The series circuit extends from terminal 66, includes winding S_1 , lead 86, winding S_3 , winding F_3 (giving an additional few volts to the series circuit for aid in starting), lead 80, filament 78, discharge device L_2 , filament 71, jumper 73, filament 70, discharge device L_1 , filament 67, lead 69, filament winding F_1 to terminal 65. Note that the arrows alongside the respective windings indicate the instantaneous voltage sense which is additive as to the windings.

There is a shunting condenser C_2 across the discharge device L_2 so that upon energization of the circuit the discharge device L_1 will ignite first, after which the voltage across the condenser C_2 will build up because of current flow. The ignition of L_2 then occurs and current by-passes through the discharge device so that the capacitive effect of C_2 is not in the circuit.

Now it will be seen that there are basically three sections to the transformer formed of the various grouping of windings heretofore described. The first section is composed of the first primary part P_1 and the first secondary S_1 . The voltage induced in the secondary S_1 contributes both as to the ignition and operation of the discharge devices. The second primary part P_2 and the second secondary winding S_2 together with the filament winding F_1 form the grouping of the second section. There is a shunt 43 between the first and second sections such that the coupling between them is loose, but not to the extent that the coupling between third and second sections is loose. The shunt 52 is better than four times as wide as shunt 43 and obviously the coupling between second section and the third section, which comprises only the third secondary winding S_3 and the remaining filament windings, is much looser than between the first and second sections. This ratio may be even greater if desired.

The winding S_3 is arranged as described, so that there will be a great deal of leakage reactance affecting the same during operation. This is the current limiting means required to give good regulation to the discharge devices, which have negative resistance characteristics when operating. The core is non-saturating in the vicinity of winding S_3 to prevent distortion of wave shape.

Speaking of distortion and wave shape, for maximum light it is best to avoid capacitive current and its accompanying distortion of wave shape. Capacitive current, for example, more readily saturates iron. If a circuit which is a simple series operating circuit for a pair of gaseous discharge device L_1 and L_2 as here is energized in the conventional way, and it is desired to correct for power factor, it is necessary to place capacitance in series with the discharge devices. The result is a distorted current through the discharge devices with decrease in lighting efficiency.

It is believed that the novelty of the invention extends to the use of a capacitive circuit across the primary in combination with a series circuit having one discharge device shunted by a starting capacitor, but in any event, the mere use of a capacitor between the junction point 84 and terminal 65 would not be totally satisfactory. The reason is that the capacitance would have to be so high that the size and cost of the capacitor would eliminate the use of such apparatus.

Several reasons are believed to account for the high efficiency of the apparatus of the invention, considering its cost and size. First, the second section serves

to isolate the primary part P_1 and its closely coupled secondary S_1 from the mutual inductive effects of the third section during operation. Thus a greater voltage is capable of being developed in P_1 and S_1 than would ordinarily be developed without the isolating section. Second, the winding S_2 in series with the capacitor C_1 affects the primary winding P_1 , P_2 but has no distorting effect upon the principal discharge device circuit since it is in parallel with a portion of same. Thirdly, the winding S_1 being closely coupled with the primary P_1 provides additive voltage for igniting and operating the discharge devices without inductive reactance of any great amount and hence need not be compensated for insofar as power factor is concerned. Furthermore, it provides additional voltage for the power factor correcting condenser C_1 keeping its capacitance low.

The sectional separation of the windings has produced a highly desirable apparatus. The wave shape is very close to sinusoidal and saturation of the core is a minimum. The power factor correction ability, notwithstanding the small condenser used (see example below) is believed accountable by virtue of isolation of the first section from the third by the second.

A practical effect of the sectionalization as described is the making available of winding space without the necessity of crowding.

It has been found that through the use of the invention a smaller and more economical ballast has been evolved than presently being made for the same requirements, and with an increase in lighting efficiency over others. Some attempt has been made to explain this by logical theory, but it is desired to emphasize that this has been only to aid in following the description. The invalidity of such theories, although sincere effort has been put into the working out of the same, in no wise would detract from the stature of the invention as represented by the structure described. Certainly the salutary results are due to a novel combination whose precise interaction may be incapable of explanation even by the most learned in this empirical and complex field. Because of this, the scope of the appended claims is intended to be limited only through the consideration of the novelty of the structures described therein in the light of pertinent prior art.

It is believed that one skilled in the art to which this invention appertains will have no difficulty in readily working out the details of a working example of apparatus embodying the invention through the explanation given above, but in order to assuage any possible doubt a commercial version of the invention will be described hereinafter.

The apparatus described was intended for the ignition and operation of two 96 inch 100 watt fluorescent lamps each of the rapid start type, rated at 800 milliamperes current, and one and one half inches in diameter (T-12). The number of turns and wire size were as follows:

P_1	258 turns, 19 gauge.
P_2	145 turns, 19 gauge.
S_1	670 turns, 25 gauge.
S_2	351 turns, 23 gauge.
S_3	815 turns, 23 gauge.

The filament windings were between 14 and 16 turns of 19 or 23 gauge wire.

The capacitors were:

C_1	5.75 mfds., 400 volts A. C.
C_2	.075 mfds., 800 volts A. C.

The proportions of the drawing with respect to the dimensions of the laminations are approximately right. The long dimension was 7.8" and the wide dimension 3". The stack height was 1 1/4 inches. Gaps 44 were .027" and gaps 50 were .058".

The fluorescent lamps were of the type which ignites at 450 volts and operate at a voltage of 135 volts. Obviously all voltages are A. C.

The device operates in this manner: When the primary P_1, P_2 is energized, a voltage will appear across the lamp L_1 which is sufficient to ignite the lamp L_1 . Because of the condenser C_2 shunting the lamp L_2 the entire voltage across both lamps will be available for the lamp L_1 by itself. This voltage in the particular example is approximately 515 volts. It is achieved as a result of the additive effects of the primary windings and the windings S_1 and S_2 .

Once L_1 is ignited, current flows through the series lamp circuit, except that no current is flowing through lamp L_2 . The flow of current through the condenser C_2 causes a voltage to appear across that condenser of sufficient value to ignite lamp L_2 after which the condenser C_2 is short-circuited by the low impedance of the lamp L_2 while same is operating.

After current flows through winding S_3 , because it is separated from the remaining principal windings by a rather large shunt, a high leakage reactance develops, acting as a deterrent to current flow. This keeps the lamps from destroying themselves, limiting the current to the rated value.

The voltages in the various parts of the apparatus are of interest in that they assist in visualizing the operation of the device.

For a line voltage, that is, a voltage across the primary parts P_1 and P_2 combined, of 118 volts the following voltages will exist:

Across the filament windings the voltage is from 4.0 to 4.1 volts on open circuit, and this drops to 3.8 volts during operation, except for the voltage across F_1 which was found to be 3 volts.

	Open Circuit	During Operation
Voltage across P_1	76	83
Voltage across P_2	42	35
Voltage across S_1	183	192
Voltage across S_2	106	85
Voltage across S_3	205	210
Voltage across L_1 and L_2	515	280
Voltage across C_1	408	395
Voltage across C_1 and S_2	302	310

Line current was 2.1 amperes, lamp current was the rated 800 milliamperes, current through the primary winding was 1.7 amperes, and current through the capacitive circuit including C_1 was 850 milliamperes.

The above apparatus gave excellent performance, both by way of good power factor correction and efficiency of lighting.

It is believed that the invention has been fully described in such a manner as not to require additional explanation.

What it is desired to secure by Letters Patent of the United States is:

1. Apparatus for igniting and thereafter providing the operating voltages for gaseous discharge devices which comprises: a pair of gaseous discharge devices one of which has a condenser shunting the same and the discharge devices being connected in series so that they will ignite in sequence by virtue of said condenser, a source of A. C. power of voltage less than that required to ignite either discharge device, a transformer having an elongate iron core, a primary winding on the core at one end thereof and connected across the source, a high leakage reactance secondary winding mounted at the other end of the core, a shunt separating the primary winding and the high leakage reactance secondary winding to provide the high leakage reactance during operation, the secondary and primary windings being in auto-transformer relationship and connected across the two gaseous discharge devices in series, and a capacitive cir-

cuit connected across the primary winding for power factor correction, said capacitive circuit comprising a second condenser and a second secondary winding mounted on said transformer core and closely coupled to the primary winding, the capacitive circuit being in parallel with a loop including the first mentioned secondary winding combined with said gaseous discharge devices.

2. Apparatus for igniting and thereafter providing the operating voltages for gaseous discharge devices which comprises: a pair of gaseous discharge devices one of which has a condenser shunting the same and the discharge devices being connected in series so that they will ignite in sequence by virtue of said condenser, a source of A. C. power of voltage less than that required to ignite either discharge device, a transformer having an elongate iron core, a primary winding on the core at one end thereof and connected across the source, a high leakage reactance secondary winding mounted at the other end of the core, a shunt separating the primary winding and the high leakage reactance secondary winding to provide the high leakage reactance during operation, the secondary and primary windings being in auto-transformer relationship and connected across the two gaseous discharge devices in series, and a capacitive circuit connected across the primary winding for power factor correction, said capacitive circuit comprising a second condenser and second and third secondary windings, the third secondary winding being in additive voltage relation with the primary winding and first mentioned secondary winding whereby said auto-transformer relationship includes the voltage thereof.

3. Apparatus for igniting and thereafter providing the operating voltages for gaseous discharge devices which comprises: a pair of gaseous discharge devices one of which has a condenser shunting the same and the discharge devices being connected in series so that they will ignite in sequence by virtue of said condenser, a source of A. C. power of voltage less than that required to ignite either discharge device, a transformer having an elongate iron core, a primary winding on the core at one end thereof and connected across the source, a high leakage reactance secondary winding mounted at the other end of the core, a shunt separating the primary winding and the high leakage reactance secondary winding to provide the high leakage reactance during operation, the secondary and primary windings being in auto-transformer relationship and connected across the two gaseous discharge devices in series, and a capacitive circuit connected across the primary winding for power factor correction, the capacitive circuit comprising a second condenser and second and third secondary windings all connected in series, the first mentioned secondary winding being connected to the capacitive circuit dividing same into two branches one being the third secondary winding and the other being the second secondary winding and second condenser in series, the third secondary winding being in voltage additive relation with the first secondary winding so that the voltage developed in said third secondary winding is available for ignition and operation in addition to those developed in said primary winding and first secondary winding.

4. Apparatus as claimed in claim 3 in which said trans-

former has filament windings coupled with windings thereof, and said gaseous discharge devices have filaments connected to said filament windings.

5. Apparatus for igniting and thereafter providing the operating voltages for gaseous discharge devices which comprises: a pair of gaseous discharge devices one of which has a condenser shunting the same and the discharge devices being connected in series so that they will ignite in sequence by virtue of said condenser, a source of A. C. power of voltage less than that required to ignite either discharge device, a transformer having an elongate iron core, a primary winding on the core at one end there-

of and connected across the source, a high leakage reactance secondary winding mounted at the other end of the core, a shunt separating the primary winding and the high leakage reactance secondary winding to provide the high leakage reactance during operation, the secondary and primary windings being in auto-transformer relationship and connected across the two gaseous discharge devices in series, and a capacitive circuit connected across the primary winding for power factor correction, the primary winding being composed of two parts, and there is a second shunt between the parts.

6. Apparatus as claimed in claim 5 in which one part, having substantially less turns than the other, is disposed between the said other part and the said secondary winding.

7. Apparatus for igniting and thereafter providing the operating voltages for gaseous discharge devices which comprises: a pair of gaseous discharge devices one of which has a condenser shunting the same and the discharge devices being connected in series so that they will ignite in sequence by virtue of said condenser, a source of A. C. power of voltage less than that required to ignite either discharge device, a transformer having an elongate iron core, a primary winding on the core at one end thereof and connected across the source, a high leakage reactance secondary winding mounted at the other end of the core, a shunt separating the primary winding and the high leakage reactance secondary winding to provide the high leakage reactance during operation, the secondary and primary windings being in auto-transformer relationship and connected across the two gaseous discharge devices in series, and a capacitive circuit connected across the primary winding for power factor correction, the primary winding being composed of two parts connected loosely coupled together, the capacitive circuit including a second secondary winding and condenser, the second secondary winding being closely coupled to one of said parts.

8. Apparatus for igniting and thereafter providing the operating voltages for gaseous discharge devices which comprises: a pair of gaseous discharge devices one of which has a condenser shunting the same and the discharge devices being connected in series so that they will ignite in sequence by virtue of said condenser, a source of A. C. power of voltage less than that required to ignite either discharge device, a transformer having an elongate iron core, a primary winding on the core at one end thereof and connected across the source, a high leakage reactance secondary winding mounted at the other end of the core, a shunt separating the primary winding and the high leakage reactance secondary winding to provide the high leakage reactance during operation, the secondary and primary windings being in auto-transformer relationship and connected across the two gaseous discharge devices in series, and a capacitive circuit connected across the primary winding for power factor correction, the primary winding being composed of two series connected parts loosely coupled one to the other on said transformer core, the capacitive circuit including two additional secondary windings and a capacitor, the said additional secondary windings being closely coupled with the respective parts, and the first mentioned secondary winding being connected in additive relationship with one of said additional secondary windings.

9. Apparatus as claimed in claim 8 in which the first mentioned secondary winding is connected to the capacitive circuit dividing the same into two branches one of which consists of the additional secondary winding with which it is in additive relation.

10. Apparatus for igniting and thereafter providing the operating voltages for gaseous discharge devices which comprises: a pair of gaseous discharge devices one of

which has a condenser shunting the same and the discharge devices being connected in series so that they will ignite in sequence by virtue of said condenser, a source of A. C. power of voltage less than that required to ignite either discharge device, a transformer having an elongate iron core, a primary winding on the core at one end thereof and connected across the source, a high leakage reactance secondary winding mounted at the other end of the core, a shunt separating the primary winding and the high leakage reactance secondary winding to provide the high leakage reactance during operation, the secondary and primary windings being in auto-transformer relationship and connected across the two gaseous discharge devices in series, and a capacitive circuit connected across the primary winding for power factor correction, the core having three windows along its length, a second shunt being disposed between the first and second windows and being substantially smaller than the said first mentioned shunt which is disposed between the second and third windows, the primary winding comprising two parts, one of which is disposed in each of the first and second windows respectively with the said first secondary winding in the third window.

11. Apparatus as claimed in claim 9 in which the capacitive circuit includes a second secondary winding which is disposed in the first window along with said one part, and a condenser in series therewith.

12. Apparatus as claimed in claim 9 in which the capacitive circuit includes second and third secondary windings disposed respectively in the first and second windows, a capacitor in series with the said second and third secondary windings, and the first secondary winding being connected in additive voltage relation only with the said second secondary winding.

13. Apparatus for igniting and thereafter providing the operating voltage for gaseous discharge devices which comprises: a pair of gaseous discharge devices one of which has a starting aid condenser shunting the same and the discharge devices being in series so that they will ignite in sequence by virtue of said condenser, a source of A. C. power of voltage less than that required to ignite either discharge device, a transformer having an elongate iron core with three winding sections thereon, the first section on one end comprising a first primary winding part and a first secondary winding, the second section in the middle comprising a second primary winding part and a second secondary winding, and the third section at the second end comprising a third secondary winding, shunts with non-magnetic gaps between sections and the shunt between second and third sections being wider than the other shunt, the primary parts being connected across the source, a power factor condenser and said first and second secondary windings being in series and together connected across the primary parts as a shunting power factor circuit, the third secondary being in series with both discharge devices and connected between one side of the source and the power factor circuit between first and secondary windings and in auto-transformer relation with both primary parts and only one of said first and second secondary windings.
